UNITED STATES PATENT OFFICE.

JOHN MACHO, OF NEW YORK, N. Y.

CLUTCH.

1,364,392.

Specification of Letters Patent.

Patented Jan. 4, 1921.

Application filed February 8, 1917. Serial No. 147,334.

To all whom it may concern:

Be it known that I, JOHN MACHO, a citizen of the United States, residing at 373 East 167th street, Bronx, New York, New York, have invented new and useful Improvements in Clutches, of which the following is a specification.

My invention relates to clutches.

The object of my invention is to provide 10 a simple means for transmitting the power from a driving shaft to a driven shaft with an actuating means which may be easily applied and easily released. My invention contemplates the use of a fluid pressure.

15 For automobile uses, an object is to provide a clutch operated by oil, under pressure, and so arranged that the oil may be put under pressure from the same source as is used for the oil feed for the engine,—in 20 common practice, a pump actuated by the usual automobile engine.

A further object is to provide a simple adjusting means for varying the pressure applied to the clutch.

25 My invention consists of the construction, combination and arrangement of parts, as herein illustrated, described and claimed.

In the accompanying drawings, forming 30 part hereof, I have illustrated a form of embodiment of my invention, in which drawings similar reference characters designate corresponding parts, and in which:

Figure 1 is a side elevation;

Fig. 2 is a horizontal section taken 35 through the working parts, one-half of the casing being removed and the control valve being omitted;

Fig. 3 is a diagrammatic plan view showing the arrangement of the connection from 40 the oil tank, and showing in section a cut-out valve;

Fig. 4 is a vertical section taken approximately along the line 4—4 of Fig. 1, looking in the direction indicated by the arrow;

45 Fig. 5 is a fragmentary detail in horizontal section of a form of pump used for producing pressure on the operating fluid; and,

Fig. 6 is a fragmentary detail in vertical 50 section of an oil feed gage and return to oil tank.

Referring to the drawings, 1 designates a fly wheel secured upon a driving shaft 2, driven by any suitable source of power,

which commonly in automobile practice is a 55 gasolene engine.

Disposed around the end of the driving shaft 2 is the upper half 3 and the lower half 4 of a casing, the adjacent edges of the halves of the casing being secured together 60 by bolts 5, and the forward end of the casing abutting channel iron 6, suitably secured to the framework of the automobile to which the apparatus is applied.

The rear ends of the halves 3 and 4 of the casing engage the forward end of a pressure cylinder 7 and are supported thereby. The rear end of the pressure cylinder 7 is supported upon channel iron 8, which extends from one side to the other of the 70 part to which the invention is applied, and is secured to the channel iron 8 by means of bolts (one of which is shown) having nuts 9 on its outer end bearing against the rear face of the channel iron 8. 75

The rear end of the driving shaft 2 is provided with a tapered portion 10, which engages in the hub 11 of a driving disk 12, the hub 11 being driven on to the tapered portion 10. 80

Secured on the rear face of the driving disk 12 is a friction, wear-resisting plate 13, formed of a material such as the common form of brake lining, removably held in position as by means of rivets 14. 85

Disposed on the hub 11, adjacent its forward face, is a grooved thrust plate 15, and disposed around the round portion of the driving shaft 2, between the channel iron 6 and the thrust plate 15, is a plurality of 90 grooved thrust plates 16. Balls 17 are disposed between the thrust plates so as to reduce the friction of the moving parts. For the purpose of retaining the hub 11 on the tapered portion 10 of the driving shaft 2, 95 a nut 18 is screw-threaded on the rear end of the portion 10 of the shaft 2. The round portion 19 is reduced in size as compared to the main body portion of the shaft 2.

A sleeve 20 is disposed on the portion 19 100 of the shaft 2 and frictionally held in a recess 21 formed in the forward end of the driven shaft 22, on the forward end of which is disposed a disk 23, arranged to abut the wear-plate 13 on the driving disk 12. The 105 disk 23 is secured by means of bolts 24 working through flanges 25 on the disk 23 and the forward end of the driven shaft 22.

Grooved thrust-plates 26 are disposed on the forward end of the driven shaft 22, and suitable friction reducing balls 27 are disposed between the thrust-plates.

- 5 A piston 28 is slidably disposed in the pressure cylinder 7 and provided with suitable packing rings 29 and also provided on its forward face with a recess 30 to receive the enlarged end of the driven shaft 22. A 10 rearwardly projecting hub 31 of the piston 28 works through a bearing 32 formed in the rear wall of the pressure cylinder 7, and suitable packing rings 33 are inserted between the adjacent surfaces of the hub 31 15 and opening of bearing 32 in the pressure cylinder 7.

A flanged ring 34 is screw-threaded into the rear end of the bearing 32 and forms a stop or limit to the movement of the piston 28, toward the right hand of Fig. 2 or toward the rear end of a motor car to which the device is applied.

An inlet pipe 35 enters one side of the pressure cylinder 7 and is connected to a 25 pump 36, the details of the construction of which are best shown in Fig. 5. This construction embodies a plurality of pistons 37, operated by cams 38 on a cam shaft 39, operated by the usual form of engine used in 30 automobile practice. The piston to the left acts as the outlet valve; the one to the right is the piston which forces the oil. An inlet pipe 40 to the pump has one end connected with the oil tank 41, which may be 35 of ordinary construction.

The pressure cylinder 7 is provided at the top with a port 42 (Fig. 4), to which is connected one end of a pipe 43, the opposite end of which is connected to the casing 44 40 of an oil feed gage, which gage is connected in turn to the oil tank 41 by means of a short pipe 47, as best shown in Figs. 3 and 6. The oil gage 44 is provided with a common form of means for control of flow 45 of the oil, as the screw-threaded members 45, as shown in Fig. 6. The oil gage is connected to the engine by means of pipes 46.

By means of a two-way valve 49 (Fig. 3), 50 disposed in the pipe 35, which leads from the pump 36 to the clutch and also to the oil gage and oil tank, the pressure may be cut out from the clutch and worked through the oil gage and back to the oil tank without operating the clutch. The two-way valve 49 is disposed in a suitable form of casing 50 on the pipe 35, and the valve casing is connected to the oil gage by means of a short length of pipe 51.

60 A port 52 is formed in the top of the pressure cylinder 7 and terminates in a chamber 53, in which chamber is disposed a valve 54, normally maintained in closed position by means of a spring 55, working 65 against a screw-threaded plug on which is

disposed a squared lock-nut, so that the tension of the spring 55 may be varied. By means of this construction, a variation of pressure behind the piston 28 may be obtained, and when an excess of pressure over that desired is obtained, the tension of the spring 55 will be overcome and such excess pressure will pass out of the cylinder 7 through the port 52 and through the pipe 43 and then to the oil gage and back to the oil tank 41.

A rod 58 is disposed through the port 42 and is provided with a cutaway portion 59 (see Fig. 1) and has its movement in one direction limited by means of a nut 60 disposed on its outer end working against the rear face of the pressure cylinder 7. The forward end of the rod 58 is provided with a lug 61, disposed in a slot 62, in an arm 63, which arm is secured on a rock shaft 64, 80 suitably supported on each side of the car to which the device is applied. An arm 65, terminating in a pedal plate 66 is secured on the rock shaft 64, so that the rod 58, forming a slide valve, may be moved to release the pressure in the cylinder 7, through the port 42 and back to the oil tank, through the pipe 43.

An arm 67, forming part of the pedal arm 65, has secured to it one end of the 95 spring 68, the opposite end of which spring is secured to the forward channel iron 6, so that the rock shaft is normally maintained in one position but may be rocked to another position by movement of the arm 65. 100

The arm 67 is provided with a projecting lug 70, working in a bifurcation 71 of an arm 72, pivoted as at 73 to an arm 74, secured on a rock shaft 75, rockably supported in bearings 75^a on the rear channel 105 iron 8. When the rock shaft 64 is moved, through the medium of the lug 70, working in the bifurcation 71, the arm 74 is rocked, carrying with it the rock shaft 75. Arms 76 secured on the rock shaft 75 carrying shoes 110 77 (as best shown in Fig. 4), which shoes 77 bear upon a flange 78 (Figs. 1 and 2) secured on the driven shaft 22. The pressure of the shoes 77 against the flange 78 causes the driven disk 23 to be withdrawn from 115 contact with the disk 12 and at the same time stops the rotation of the driven disk 23 and the shaft 22.

For the purpose of limiting the movement of the arm 74 toward the forward end of 120 the device and for adjusting the movement thereof, a boss 79 (Fig. 1) is formed on forward face of the arm 74 and provided with a screw-threaded body 80 adapted to abut the rear edge of the channel iron 8 secured on the car. A nut 81 locks the screw-threaded body 80 to the arm 74, providing an adjusting means for the throw of the arm 74. A suitable coil spring 82 (Fig. 4) is disposed around the rock shaft 75 and ar- 125 130 135

ranged to keep the brake shoes 77 away from the flange 78 when the clutch is engaged. When the pressure is removed by operation of the pedal 66, the lever 74 is 5 rocked toward the right hand of Figs. 1 and 2 and the tension of the spring 82 is overcome and the shoes 77 forced against the flange 78 and the clutch disengaged.

A suitable drain cock 83 and filler plug 10 84 may be arranged on the halves 3 and 4 of the casing surrounding the clutch.

In the operation of the device, a flow of oil from the tank 41 is produced by means of any suitable form of pump 36, operated 15 in any way from the ordinary form of engine used in automobile practice. The same pump which produces this pressure is utilized in applying lubricant to the engine in the usual way.

20 With the cut-out valve 49 in the position shown in Fig. 3, the oil is forced through the pipe 35 into the cylinder 7. The valve 58 being closed, the pressure is exerted against the piston 28, forcing the shaft 22 25 toward the left-hand the shaft 22 being slidably disposed in the piston 28 (Fig. 2) so that the disk 23 contacts with the disk 12 and rotation from the shaft 2 is communicated to the shaft 22. With the parts in this 30 position, the shoes 77 are retracted from the flange 78 by the tension of the springs 82. The valve 58 being opened by the rocking of the rock-shaft 64, the pressure in the cylinder 7 is relieved and the shaft 75 being 35 simultaneously rocked overcoming the tension of the spring 82, the shoes 77 contact with the flange 78 and the shaft 22 is slid to the right-hand of Fig. 2, so that the disk 23 is retracted and at the same time the pressure 40 of the shoes 77 against the flange 78 stops the rotation of the parts.

With the valve in the position shown in Fig. 3 and the pump 36 being in action, pressure is produced in the cylinder 7 causing 45 the piston 28 to be forced to the left hand of Fig. 2, and the consequent engagement of the clutch. Operation of the pedal 66 rocks the valve 49 90° in a clockwise direction, so that its diametral passage is 50 brought into alignment with the pipe 35 and the passage 51. This cuts off the pressure to the clutch and permits circulation of the oil through pipe 40, pipe 35, the diametral passage of the valve 49, passage 51, oil gage 44, 55 pipe 47 and back to the tank 41. By this

arrangement the pump 36 may continue to work with the car standing still without producing pressure on the cylinder 7.

Having thus fully described my invention, what I claim as new and desire to secure by 60 Letters Patent is:

1. A clutch comprising the combination of a driving shaft, a driven shaft slidably disposed adjacent the driving shaft and arranged to telescope thereover, abutting disks 65 arranged on the driving and driven shafts respectively, a pressure cylinder arranged around the driven shaft, a piston in the cylinder arranged to move the slidable shaft and means for producing pressure in the 70 cylinder behind the piston.

2. A clutch comprising the combination of a driving shaft, a driven shaft slidably disposed adjacent the driving shaft, abutting disks arranged on the driving and 75 driven shafts respectively, a pressure cylinder arranged around one of the shafts, a piston in the cylinder arranged to force the disks into contact, means for producing pressure in the cylinder behind the piston, 80 a casing disposed around the disks and adjacent parts, grooved thrust plates on the shafts and balls disposed between the grooved thrust plates.

3. A clutch comprising the combination 85 of a driving shaft, a slidably supported driven shaft, disks on the adjacent ends of the shafts, a piston provided with a sleeve fitted around the driven shaft, a cylinder arranged to receive the piston, means for producing pressure in the cylinder, a spring 90 pressed adjustable member on the cylinder arranged to be operated at a predetermined pressure to relieve pressure in the cylinder, and means for controlling pressure in the 95 cylinder.

4. A clutch comprising the combination of a driving shaft, a slidably supported driven shaft, disks on the adjacent ends of the shafts, means for forcing the disks into contact, a projecting member on the driven shaft, a rock shaft disposed adjacent to the projecting member, shoes carried by the rock shaft and adapted to contact with the projecting member and means for rocking 100 the rock shaft when the pressure producing means is inoperative.

In testimony whereof I have signed my name to this specification.

JOHN MACHO.
